CLAIM

The ornamental design for a stock for a gun, as shown and described.

DESCRIPTION

FIG. 1 is a top perspective view of a stock for a gun in accordance with my new design, the stock for a gun being in a fully deployed configuration;

FIG. 2 is a front, left, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another top perspective view of the stock for a gun, the stock for a gun being in a collapsed configuration;

FIG. 10 is a front, left, bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines immediately adjacent the shaded areas represent the bounds of the claimed design. All broken lines are directed to environment and are for illustrative purposes only and form no part of the claimed design.

1 Claim, 12 Drawing Sheets
